BATTERY TERMINAL

Nicholas John Zam, Toledo, Ohio, assignor of thirty per cent to Albert J. Kairis and thirty per cent to Gerrit Van Westrienen, both of Detroit, Mich.

Application May 1, 1942, Serial No. 441,313

1 Claim. (Cl. 173—259)

This invention relates to improvements in battery terminals, and has for its object the provision of a novel, simple and efficient clamp of this character which is operable to effect a positive clamping to or release of a terminal from a battery post and is easily and quickly adjustable to suit posts of different sizes.

The invention is fully described in the following specification, and illustrated in the accompanying drawing, in which—

Figure 1 is a top plan view of a terminal embodying the invention applied to the post of a battery, with the battery fragmentarily shown; Fig. 2 is an enlarged section on the line 2—2 in Fig. 1, with a lever arm applied to an end of the screw member to turn the same; Fig. 3 is a side elevation of Fig. 1; Fig. 4 is a plan view of a clamp similar to Fig. 1, with the lever arm applied thereto centrally of the clamp lugs instead of at one end of the screw member; Fig. 5 is a side elevation of Fig. 4; Fig. 6 is a side elevation of the adjusting sleeve employed in connection with the screw member, and Fig. 7 is a side elevation of the screw member.

Referring to the drawing, 1 designates a terminal post of a battery 2, and 3 a terminal embodying the invention and connected to a suitable electrical lead 4.

The terminal 3 includes a body or clamping member 5 having an electrical lead connecting portion 6 and a split post clamping portion 7, the latter being adapted to straddle a post so as to have clamping engagement therewith, as well understood in the art. Each half of the split portion 7 terminates at its free end in a lug 8 disposed at one side of a clamp post and being substantially parallel to and spaced from the other lug 8, as shown.

The lugs 8, 8 are connected by a screw member 10 which threads in axially aligned apertures in the lugs 8 with the threaded connection of one lug being of the right hand type and that of the other lug being of the left hand type, so that a turning of the screw member will effect a uniform contracting or expansion of the clamping member.

To facilitate turning the screw member 10, a lever arm 12 may be attached to one end of the member as shown in Fig. 2, or a lever member 13 may be mounted on the screw member between its two thread sections and between the lugs 8, 8, as shown in Figs. 4 and 5.

Inasmuch as the posts 1 for different batteries may vary in size, it is important to provide means for effecting an adjustment of the thread-

ed connection with one or the other of the terminal lugs, so as to adapt the terminal for posts of different sizes. It is also desirable in terminals of this character to have a slight turn of the screw member, for instance a quarter or a half turn, effect a sufficient expansion or contraction of the clamping portion 5 to release or engage a post. Otherwise, the battery, to the post of which a terminal is clamped, might interfere with the adjusting movements of the control levers 12 or 13.

The present invention accomplishes this adjustment by mounting a sleeve 15 in the screw member receiving aperture of one lug 8 for turning movements therein and by threading one end of the screw member 10 in such sleeve, while the other member thereof is threaded in the other lug of the pair. This sleeve at one end is provided with a tool engaging portion 15^a to facilitate turning the sleeve for adjustment in the lug. The sleeve is secured in adjusted position by a set screw 16 engaging it through a side of the lug in which mounted. It is desirable to have the set screw engage the sleeve within an annular recess 17 in its periphery and to make the recess sufficiently deep so that the set screw may be released from holding engagement with the bottom of the recess and at the same time engage the side walls of the recess to prevent axial movements of the sleeve relative to the lug when adjustment is being effected. This adjustment of the sleeve causes it to turn in one direction or the other on the screw member, so as to shorten or lengthen the spacing between the two lugs 8 to suit the post to be engaged.

By the use of this adjusting means, a nice adjustment of the clamping action may be effected to suit the particular post in connection with which the terminal is to be used, so that a slight turning of the screw member and its control arm will effect an efficient engagement or release of the terminal with respect to the post.

I wish it understood that my invention is not limited to any specific construction, arrangement or form of the parts, as it is capable of numerous modifications and changes without departing from the spirit of the claim.

Having thus described my invention, what I claim as new, and desire to secure by United States Letters Patent, is:

In a battery terminal having a split post-clamping member with lugs projecting in substantially parallel relation from the halves thereof and provided with axially aligned apertures, a

sleeve axially insertable and mounted for rotary adjustment in the aperture of one lug and having provision at one end for the engagement of an adjusting tool therewith, said sleeve having a peripheral recess, a set screw threaded in the lug and engaging in the recess to prevent axial movements of the sleeve in the lug and also to releasably hold the sleeve in adjusted position,

and a screw member having a right thread at one end and a left thread at the other end with one end threading into the sleeve and the other end threading into the aperture of the lug not carrying the sleeve, whereby a turning of the screw member will expand or contract the clamp member.

NICHOLAS JOHN ZAM.
